LEAK DETECTOR

John A. Roberts, Lynnfield Center, Mass., assignor to
General Electric Company, a corporation of New York

Application June 9, 1958, Serial No. 51,264

Term of patent 14 years

(Cl. D52—1)

Figure 1 is a top perspective view of a leak detector, showing my new design;

Figure 2 is a top view thereof; and

Figure 3 is a side view thereof.

The portion of the bottom not shown remote from the handle has substantially the same appearance as the top view shown.

The dominant features of my new design are shown in solid lines in the drawings.

I claim:

The ornamental design for a leak detector, as shown and described.
